His Attorney.

UNITED STATES PATENT OFFICE

WILLIAM J. WOODS, OF SCHENECTADY, NEW YORK, ASSIGNOR TO GENERAL ELECTRIC COMPANY, A CORPORATION OF NEW YORK

HYDRAULIC OPERATOR

Application filed September 30, 1930. Serial No. 485,474.

My invention relates to electro-hydraulic operating means of the general character described and claimed in a copending application of Walter O. Lum, Serial No. 415,341, filed December 19, 1929 and assigned to the assignee of the present invention.

In the device of the Lum application referred to above to obtain compactness the movable piston carries and houses the pressure generating impeller concentrically therein, a splined shaft permitting relative movement between the impeller and the stationary driving motor therefor as the piston is moved. With this construction all of the fluid must pass through the impeller both upon operation of the impeller to raise the piston as well as when the driving motor is deenergized to permit the piston to return to its initial position. This results in a piston construction of rather complicated design which restricts the passage of oil. Furthermore, in order to create the pressure necessary for quick operation of the piston, impellers of large diameter relative to the piston and of correspondingly large moments of inertia have been used. The large moment of inertia of the impeller as well as the materially restricted oil passages through the piston hinder a quick return of the piston which in certain service is one of the requirements for a device of this character.

Hence it is the principal object of my invention to provide an improved concentric type of electro-hydraulic operating device which is compact but in which complicated piston structures are eliminated and quicker reset of the piston upon deenergization of the device is obtained.

In the preferred embodiment of my invention I provide the fluid casing for the concentric piston and impeller with a cylinder or sleeve formed with passageways for the passage of oil around the piston which slides in the sleeve. In addition a concentric oil tube extends from the top of the casing through the piston and cooperates with the cylinder to form a stationary housing for the impeller which is driven by an electric motor mounted on the top of the casing,

the driving shaft extending downwardly through the oil tube. The impeller is specially designed with relatively wide blades in comparison to the diameter of the impeller in order to deliver a large volume of oil to the under side of the piston. The wide blades of small diameter permit the use of the same size motor as previously used without overload to deliver a volume of oil necessary for fast operation. With this construction a very compact unit is obtained by arranging the impeller and piston in concentric cooperating relationship with the minimum amount of space necessary to house both elements. Also since the impeller does not move with the piston the splined shaft is eliminated and the piston structure is greatly simplified having simply an opening therein to permit the extension of the oil tube therethrough. Moreover with the specially designed impeller and the large and gradually curving passageways in the housing the piston will reset rapidly, upon deenergization of the driving motor, the oil flowing freely through the orifices and through and around the piston, making it necessary for only part of the oil to pass through the piston, thus increasing the rate of flow of oil to the upper side of the piston which increases the speed with which the piston will return to initial position.

In the drawing Fig. 1 shows a cross section of my invention and Fig. 2 shows a detailed construction of the cylinder used in the hydraulic operator shown in Fig. 1. Fig. 3 is a graph showing time load relationship for the hydraulic operator.

In Fig. 1 the casing 10 is provided with the cover 11 which supports the electric motor 12 which drives the impeller 19 by means of the shaft 20. Within the casing 10 is the sleeve or cylinder 13 having a head 13' with an opening therethrough and supported by the abutment 10' of the casing 10 and secured thereto by means of the pin 15. The oil tube 17 is fastened to the cover 11 by suitable screws and extends toward the cylinder head 13' by means of its flared end 17₁ and forms therewith a housing for the impeller 19. This housing provides passage-

ways such as 17' which are free from intricate curves and provide a smooth passage for the oil which prevents a turbulent flow of oil therethrough upon operation of the 5 impeller or upon a return of the fluid through the housing upon resetting of the piston. The cylinder 13 is provided with spacing elements 14 as shown in Fig. 2. Thus passageways such as 16 are provided 10 between the casing 10 and the cylinder which permit the oil to reach the underside of the impeller 19 around the piston 21. Oil is also led to the top of the impeller 19 through the oil tube 17 provided with the openings 15 18 therein, it being noted that the oil level is above these openings. The piston 21 slides within the sleeve 13 and has an opening therein through which the oil tube 17 extends. Supported by the piston 21 are the 20 push rods 22 and 23 having a bridging member 24 supporting the work engaging eye 25. The casing 10 is provided with the eye 26 permitting pivotal support of the entire unit.

One of the most desirable characteristics 25 in certain service of fluid pressure operated devices such as my hydraulic operator is to have a quick operation and quick reset of the piston. I have found that by increasing the relative width of the blades of the impeller with respect to the diameter a greater 30 volume of oil can be delivered without overloading the motor. This is due to the fact that although the blades are made wider the load on the motor increases more rapidly 35 with an increase in the diameter of the impeller blades than with an increase in the width of the blades. The resulting low moment of inertia of the impeller and oil entrapped therein causes it to quickly come 40 to rest when the motor is deenergized, thus minimizing the delay in the starting of the reset of the piston to its initial position. This calls for larger orifices in the impeller housing which decreases the turbulence of 45 the flow of oil through the housing. Making the impeller stationary and extending the drive shaft through the piston proper makes it possible to greatly simplify the passageways of the impeller housing as can 50 clearly be seen from Fig. 1. The simplified passageways in the housing proper, and the passageways provided for by-passing the oil around the piston instead of passing the entire volume of oil through the piston proper 55 permits a very rapid return of the piston upon deenergization of the impeller since unrestricted passageways are thereby provided for the return flow of the oil.

The time load relationship for normal 60 working loads of my new design operator are shown in Fig. 3, the time being marked in tenths of a second along the X axis and the load in pounds along the Y axis. Of course these relationships will not hold when 65 absolute maximum loads other than those

for which the operator is designed are applied to the operator. Curve 1 represents the time required for the various loads before the piston starts to settle; curve 2 the time required after starting for the travel of the piston from its upper position to its lower position. Curve 3 shows the total time required for the various loads; curve 4 the time required before the piston starts in its upward movement; curve 5 the time required for the piston to move from its lower position to its upper position and curve 6 the total time required for movement of the piston from its lower position to its upper position. Curve 7 is an approximate representation of the time required for resetting of the prior type of hydraulic operator referred to above in the Lum application. It will be seen that curves 2 and 3 show that the time required for resetting, that is for the piston to move from its upper to its lower position upon deenergization of the operator, is substantially independent of the load operated upon between limits for which the operator is designed which was not true of the old type of operator as can be seen from the approximate curve 7. It will be noted further that for a given operator there is one load where the total time required for resetting and the total time required for movement to the upper position are the same. This load, therefore, when applied to the operator will cause the operator to move to either position in the same length of time. Practically the entire operation of the device is completed within a few tenths of a second, the curves being taken from an actual test run upon the new type of operator. The ideal condition, of course, would be to have the operator reset within the same length of time independently of all loads which condition is substantially provided by my new type of operator. It will be also observed that the time for resetting with a minimum load is not greater than the time for operation of the operator to its upper position with a maximum load as can be determined from a study of the curves #3 and #6.

The operation of the device is as follows: 115 When the motor 12 is energized the impeller 19 will rotate. Oil is directed to the upper part of the impeller by means of the oil tube 17 provided with the openings 18 therein through which the oil flows from above the piston to the upper part of the impeller. Oil is also directed from the casing above the piston through the passageways between the cylinder and the casing to the under side of the impeller. It will 120 thus be observed that only part of the oil must pass through the piston. The impeller forces the oil in a radial direction through the passageway 17' thus creating a pressure differential between opposite 125 130

sides of the piston 21 to move it upwardly in a vertical direction. When the piston reaches its upper limit the impeller continues to provide a pressure differential to support the piston without delivering more oil to the underside of the piston proper. In this upper position of the piston the impeller will spin in the oil to maintain the pressure differential. Upon deenergization of the driving motor 12 the impeller quickly comes to a standstill as the energy of the rotor of the motor is expended and the pressure soon drops, permitting the piston to return to its initial position. This return or reset of the piston is rapid because the passageways provided in the housing as explained above are devoid of complicated turns and are large and because only part of the oil needs to pass through the piston proper, substantially half of the oil being by-passed around the piston by means of the cylinder and casing combination.

It will thus be seen that I have provided a fluid pressure operated device or hydraulic operator in which I have greatly simplified the construction and in which I provide quick reset of the piston which heretofore has been impossible with hydraulic operated piston designs of more or less complicated structure.

The embodiment of the invention illustrated and described herein has been selected for the purpose of clearly setting forth the principles involved. It will be apparent, however, that the invention is susceptible of being modified to meet the different conditions encountered in its use, and I, therefore, aim to cover by the appended claims all of the modifications within the true spirit and scope of my invention.

What I claim as new and desire to secure by Letters Patent of the United States, is:

1. A hydraulic operator including a fluid casing, a piston operable in the casing, and a pump immersed in the fluid and having its inlet and outlet passages connected to create a differential in the fluid pressure on the opposite sides of the piston to move said piston, a housing for said pump, and a fluid guide tube extending through the piston, said tube providing a fluid inlet to said pump housing.

2. A hydraulic operator including a fluid container, a cylinder immersed in the fluid in said container, a piston movable in the cylinder, and a double inlet impeller pump mounted at the head end of the cylinder and discharging therein for creating a differential in the fluid pressure on the opposite sides of the piston, and having one inlet extending through the head of the cylinder and the other inlet extending through the piston.

3. A hydraulic operator including an impeller pump immersed in a fluid, a pair of separable concentrically disposed tubes having means at the adjacent ends thereof forming a housing for said impeller with the discharge directed between the tubes, said tubes providing inlet passages to said impeller pump and an annular piston disposed between the tubes to be operated by the fluid pressure created upon rotation of the impeller.

4. A hydraulic operator including a double inlet impeller immersed in a fluid, an inlet tube for one side of the impeller having means at the end thereof forming one side of a separable housing for the impeller, a cylinder concentrically surrounding the tube and the impeller and having a head forming the other side of said separable housing provided with an inlet for the other side of the impeller, the discharge of said housing being directed into the space between the tube and the cylinder, and a piston having a sliding engagement with the outside of the tube and the inside of the cylinder to be operated by the fluid pressure created upon rotation of the impeller in said housing.

5. A quick reset hydraulic operator including a fluid casing, a piston movable in the casing between two positions, a work engaging member connected thereto, an impeller pump mounted at one end of the casing for creating a pressure differential in the fluid on opposite sides of the piston to move said piston to one of said positions, a housing for said pump, a fluid guide tube extending through said piston and providing an inlet to said housing, said piston sliding on said tube, said impeller pump being designed for a given load to permit a return movement of said piston to its other position in the substantially same length of time required for movement to said one position.

6. A quick reset hydraulic operator provided with a fluid casing, a piston immersed in a fluid therein and movable between two positions, a load engaging member connected thereto for engaging loads of various degrees, an impeller pump therein for creating a pressure differential to move said piston to one position, a housing for said pump and a tube extending through said piston for conducting fluid to said pump housing, said pump having a drive shaft extending through said tube, said piston sliding on said tube, said pump and housing being designed to permit a quick movement of said piston to its other position, the time for said movement being substantially independent of the load engaged by said work engaging member between wide limits.

7. A quick reset hydraulic operator provided with a fluid casing, a piston immersed in a fluid therein and movable between two

positions, a load engaging member connected thereto for engaging loads of various degrees, an impeller pump therein for creating a pressure differential to move said piston 5 ton to one position, a housing for said pump having a fluid guide tube for conducting fluid to said pump housing through said piston, said piston sliding on said tube, said pump and tube being designed so that the 10 time required for the piston to move to its other position with minimum load is not greater than the time for movement to said 15 one position with maximum load.

8. A quick reset operator including a piston 15 ton immersed in a liquid and movable between two positions, a double inlet impeller for creating a pressure differential to operate said piston, means for conducting fluid through said piston and around said piston 20 ton to both sides of said impeller, said impeller being designed with relatively wide blades in comparison with its diameter whereby a large volume of fluid is quickly delivered to the face of the piston to obtain 25 rapid movement thereof to one position, said conducting means forming a housing having gradual curved passageways permitting a free return flow of fluid through said housing without turbulence to permit a 30 rapid movement of said piston to its other position, the time for movement of said piston to said one position being for a given load substantially equivalent to the time for movement to its other position.

35 9. A quick reset hydraulic operator including a piston immersed in a liquid and movable between two positions, a pressure creating impeller for moving said piston to one of said positions, said impeller being 40 of such proportions as to deliver a relatively large volume of liquid in operation, a means for conducting liquid through said piston to one side of said impeller, other means for conducting fluid around said piston 45 ton to the other side of said impeller, said conducting means providing a housing for said impeller and having relatively gradual curved passageways permitting a free return flow of fluid through said housing to 50 permit a rapid movement of said piston to its other position.

10. A hydraulic operator including a fluid casing, a piston immersed in a fluid therein and movable between two positions, an impeller 55 for creating a pressure differential for moving said piston to one of said positions, means for conducting fluid through said piston to one side of said impeller, a cylinder in said casing in which said piston 60 moves and passageways formed by said cylinder and casing for directing fluid to the other side of said impeller, said conducting means and passageways providing return means for the fluid when said piston moves 65 to the other position.

11. A hydraulic operator including a fluid casing, a piston, an impeller pump having a drive shaft extending through said piston, said piston having relative movement with respect to said impeller, a cylinder provided with a head integral therewith within said casing in which said piston moves, a fluid tube having a flared end extending through said piston and concentric of said drive shaft, the flared end of said tube and the head end of said cylinder forming a housing for said impeller pump. 70

12. A hydraulic operator including a fluid casing, a fluid therein, an impeller pump having a drive shaft centrally disposed in said casing, a tube concentric of said impeller shaft and provided with a flared end, a cylinder provided with a head integral therewith mounted in said casing, the head end of said cylinder and the flared end of said tube forming a housing for said impeller pump, and a piston immersed in said fluid within said cylinder, said tube extending through said piston, said piston being movable with respect to said tube in 80 response to operation of said impeller pump. 85

13. A hydraulic operator including a fluid casing, a fluid therein, an electric driving means mounted at one end of said casing, an impeller rotatably mounted and centrally disposed in said casing and connected to be driven by said driving means, a fluid guide tube extending within said casing, a cylinder in said casing, a piston immersed in said fluid within said cylinder and movable therein, said tube extending through said piston, said cylinder and tube forming a housing for said impeller, said piston having a movement parallel to said tube in 90 response to operation of said impeller. 95

14. A hydraulic operator including a fluid casing, a cylinder mounted in said casing and providing passageways between the cylinder and said casing, a fluid tube disposed centrally of said casing and extending toward and adjacent said cylinder, a piston movable in said cylinder, said tube extending through said piston, said piston being 100 slideable thereon, a double inlet impeller having a shaft extending through said tube, said tube and cylinder forming a housing for said impeller on one side of said piston, said impeller receiving fluid through said tube and said passageways formed by said cylinder and casing and expelling the same 105 through the housing formed by said tube and cylinder in a radial direction to create a pressure differential on one side of said piston whereby said piston will move in response thereto. 110

15. A quick reset hydraulic operator including a fluid casing, an electric motor mounted at one end of said casing, an impeller rotatably mounted and centrally disposed in said casing and connected to be 115

driven by said motor, said impeller being designed to deliver a relatively large volume of fluid during operation, a fluid guide tube extending within said casing, a cylinder 5 in said casing, a piston within said cylinder movable between two positions, said tube extending through said piston, said piston having a movement parallel to said tube to one position in response to operation of said 10 impeller upon energization of said motor, said cylinder and tube forming a housing having relatively gradual curved passageways for said impeller permitting a free return flow of fluid through said housing to 15 permit a rapid movement of said piston to its other position upon deenergization of said driving means.

16. A hydraulic operator including a fluid container, a piston movable therein, a double inlet impeller for discharging fluid under pressure against one side of said piston, and a tube extending through said piston for conducting fluid from the other side of said piston to one inlet of said pump, and 25 other means for conducting fluid from said container to the other inlet of said pump.

17. A hydraulic operator including a fluid container, a piston movable therein, a load engaging member connected thereto, an impeller pump mounted in the bottom of said container for discharging fluid against one side of said piston to move the same, a housing for said pump and a fluid inlet tube extending through said piston to an intake 35 of the pump housing for conducting fluid from the other side of the piston to said pump housing, said piston sliding on said tube and said pump having a driving member extending through said tube.

40 18. A hydraulic operator provided with a fluid casing, a piston immersed in the fluid and movable therein, a load engaging member connected thereto, an impeller pump therein for creating a pressure differential 45 to move said piston, and a fluid guide tube extending through said piston to the inlet of said pump for conducting fluid thereto, said piston sliding on said tube and said pump having a driving member extending 50 through said tube.

19. An electro-hydraulic operator unit including a substantially closed container, a liquid therein, an electric motor mounted on the top of the container and having a shaft 55 extending into said liquid, an operating member extending into said liquid through the top of the container, a piston connected to said operating member and immersed in said liquid, said piston being movable between two positions and biased to one of said positions, an impeller pump connected to said motor shaft and immersed in said liquid, a tube extending through said piston for conducting fluid to said pump, and 60 other means disposed below the level of the 35

liquid and cooperating with said tube for connecting the inlet and outlet of said pump to create a pressure differential on opposite sides of the piston to move said piston to the other position. 70

20. A hydraulic operator having a fluid casing, a piston therein movable between two positions and biased to one of said positions, a double inlet impeller pump in said casing for creating a fluid pressure therein 75 to move said piston to the other position, a housing for said pump having a fluid guide tube extending through said piston, said piston being slidable on said tube, a motor for driving said impeller pump and a drive shaft for connecting said motor and pump, said shaft extending through said guide tube, said guide tube providing an inlet for said pump housing.

In witness whereof, I have hereunto set 85 my hand this 29th day of September, 1930.
